UNITED STATES PATENT OFFICE.

THOMAS BILYEU, OF PORTLAND, OREGON, ASSIGNEE, BY MESNE ASSIGNMENTS, TO
INTERNATIONAL MONEY MACHINE COMPANY, OF TERRE HAUTE, INDIANA, A
CORPORATION OF INDIANA.

PAPER-MONEY DELIVERER.

1,178,377.

Specification of Letters Patent.

Patented Apr. 4, 1916.

Application filed January 18, 1913. Serial No. 742,958.

To all whom it may concern:

Be it known that I, THOMAS BILYEU, a citizen of the United States, residing at Portland, in the county of Multnomah and 5 State of Oregon, have invented certain new and useful Improvements in Paper-Money Deliverers, of which the following is a specification.

A certain type of mechanical cashier 10 heretofore proposed includes instrumentalities for mechanically paying out money in the form of coins and bills. The means for delivering bills from the machine mentioned comprises pivoted delivery or suction members adapted to pick up a bill from a pile 15 and by pivotal movement, carry said bill to a point of delivery.

The present invention involves improvements in the said paper currency or bill paying mechanism, an important object being 20 to simplify the same and to so construct the delivery members themselves that the latter have a straight line movement in carrying the bill to the point of delivery. The delivery mechanism is rendered very dependable by the present improvements and the space necessary for operation of the delivery members is greatly economized. Pneumatic 25 or suction bill delivery devices are also utilized in the present machine and bill holders adapted to support a pile of bills are associated with the delivery devices and are susceptible of operation, also through pneumatic means, in order to coöperate with the 30 delivery devices in effecting initial separation of a bill from the pile preliminary to its delivery.

The invention involves additionally, other 35 special features of construction and arrangement of parts that will be more fully set forth in the following detailed description, and in the accompanying drawings, in which—

Figure 1 is a top plan view of a currency 40 handling machine comprising the essential features of the invention, a portion of the casing of the machine and keyboard being broken away to bring out the arrangement of interior parts. Fig. 2 is a view looking 45 toward the end of the machine, the end casting plate removed, and illustrating by dotted lines the extent of delivery movement of the deliverers, and also the range of movement

of the bill holders which supply the deliverers. Fig. 3 is an enlarged plan view of 55 one of the delivery mechanisms alone. Fig. 4 is a view similar to Fig. 2 but looking at the mechanism illustrated from the opposite side of the same. Fig. 5 is a rear view of the mechanism illustrated in Fig. 2, dotted 60 lines showing the deliverer upraised as when lifted to facilitate the introduction of a new supply of bills upon the associated bill holder. Fig. 6 is a detail fragmentary view of the latch and guide mechanism for each 65 deliverer. Fig. 7 is a detail view, parts broken away, bringing out more clearly the operative connection between a key and its selector. Fig. 8 is a combined view illustrating one of the selector clutches, looking 70 from the front and from the side thereof.

In the drawings, A denotes the casing of the machine, the same having the keyboard B at its right hand end, and a plurality of holders C at the left of said keyboard, a 75 deliverer D being associated with each holder. It is contemplated that any suitable number of bill holders C may be employed, those illustrated, however, being designed to supply bills of different denominations to the respective deliverers. The capacity of the machine is such that bills of one dollar, two dollar, five dollar, ten dollar and twenty dollar denominations are carried in piles or packs disposed on the 85 holders C, the latter being virtually vertically movable tables or platforms that are operated in a manner which will appear fully hereinafter. A main actuator or handle E at the right hand end of the machine 90 is adapted to operate an ejector shaft 1 mounted in suitable bearings in the casing A and extending longitudinally the entire length of said casing.

By referring to Fig. 2, it will be observed 95 that the holder C is supported at the upper end of a rod 2, the lower end of which is secured to a piston 3 which operates vertically in a cylinder 4 carried on the base of the machine. The holder C has a depending 100 guide member 5 operating in a tubular guide 6 and by this means a proper movement of the holder is prescribed. The holder C consists primarily of a plate having a number of apertures or openings 7 and an associated 105 deliverer D arranged above the holder is of

somewhat T-shape and comprises a hollow body having apertures in its under side. A tubular arm 8 connects the deliverer D with a pipe 9 arranged in a plane above the holder C, said pipe receiving at its rear end a pipe 10 which extends horizontally from a vertical pipe 11 at the rear portion of the machine. The pipe 11 is in turn connected at its lower end with a horizontal pipe 12 which leads to a main air or suction conduit 13 that extends almost the entire length of the casing A and is connected with any suitable suction creating device 13^a see Fig. 1. The connection between the pipes 9 and 10 is such that the pipe 9 is virtually swiveled on the pipe 10. This connection is necessary to permit the deliverer D to be raised by a sort of pivotal movement with the pipe 9 as its axis, in order that a supply of bills or equivalent currency may be disposed on the coöperating holder C, as shown in dotted lines in Fig. 5 of the drawings. Normally, however, the deliverer D is held in a horizontal position by the provision of a latch mechanism which includes the slide catch 14 that engages a slotted guide 15 upon a standard 16 secured to the base of the machine.

It is contemplated that the deliverer D shall have reciprocal movement in its delivery operation and the catch 14 works back and forth in the slot of the guide 15 during such movement of the deliverer. Suitable finger pieces 17 are grasped by the operator in order to retract the catch 14 sufficiently to disengage it from the guide 15 and the latch mechanism is shown quite clearly in Fig. 6 of the drawings.

The pipes 9, 10, 11 and 12 and the tubular arm 8, being all in communication with one another, and connected with the conduit 13, establish a connection between the conduit and the deliverer D, whereby a suction may be created in the deliverer through the openings in the bottom of the latter. It is obvious therefore that if the pile of bills carried by the holder C is lifted sufficiently to bring the uppermost bill into engagement with the deliverer D, a subsequent lowering of the holder C will separate said uppermost bill from the pile of bills due to the fact that the suction created in the deliverer is sufficient to firmly hold said bill against the under side of the deliverer. An operating means is therefore provided for moving each holder C toward and from its deliverer and such means will now be set forth in detail.

Connected with the rod 2 which supports the holder C, is a transverse bar 18 which projects from opposite sides of the rod 2 and has attached to one of its end portions a link 19. The link 19 is secured to a control lever 20 which is pivoted intermediate its ends on a bracket 21, the rear ex-

tremity of the lever 20 being connected with a tension spring 22 that normally tends to move the front end of the lever and the holder C upwardly. From the pipe 12 previously mentioned leads a branch pipe 23 that communicates with the lower end of the cylinder 4. The suction created in the air-line conduit 13 is sufficiently great that the tendency to create a vacuum in the lower portion of the cylinder 4 will cause the piston 3 to be retained at the lower limit of its movement in the cylinder, and thereby maintain the holder C at the lower extreme of its movement under normal conditions, notwithstanding the tension of the spring 22. The end of the bar 18 opposite that connected with the link 19 is adapted to be engaged by a catch 24 of a locking member 25. The locking member 25 is of peculiar form, practically L-shape, the long arm of said member being pivotally connected at 26 to an ejector arm 27. A suitable bearing 28 is provided for the locking member 25 and operates through a slot 29 in the middle portion of said member, which slot is offset at one end. A spring 30 anchored to the base of the machine at one end is attached at its other end to the ejector arm 27 and normally holds the latter retracted or in a rear-most position. The ejector arm 27 for each holder and delivery mechanism is loosely mounted upon the main shaft 1 and each arm 27 is bifurcated at its upper extremity to engage with a stud 31 carried by the rear end of the pipe 9, which, as before mentioned, has a swivel and telescopic connection with the pipe 10.

Upon the shaft 1 which loosely carries the several ejector arms 27 are also mounted rigidly a plurality of clutch members 32 of special construction, and each clutch member is pivoted at its lower end to a collar 33, rigidly secured to the shaft 1 and a spring 34 is connected at one end to the clutch member and at its opposite end to an arm 35 offstanding from said collar. A lateral catch 36 is formed with the clutch member 32 and said member 32 is operable by a selector bar 37. The bar 37 is pivotally supported at its front end, as shown at 38 and a rod 39 connects said bar 37 intermediate its ends with the bell crank 40 of a shaft 41 mounted in bearings on the casing A beneath the keyboard B. A key 42 is secured at its lower end to one arm of the bell crank lever 40, the other arm being secured to the rod 39 aforesaid. By depressing the key 42 to tilt the lever 40, the selector bar 37 is moved horizontally to engage and force the clutch member 32 to a position in rear of the adjacent ejector arm 27, against the tension of the spring 34. In this manner, the catch 36 engages the ejector arm and holds the clutch member 32 in co-operative relation with respect to said arm,

whereupon, should the shaft 1 be rotated partly by the handle E, it is obvious that the rigidly mounted clutch member 32 carried thereby will be oscillated sufficiently to impart corresponding movement to the ejector arm. Movement of the ejector arm in this manner will reciprocate the deliverer D. Since an understanding of the particular time of operation of the different mechanisms of the machine is important to a comprehension of the advantages of the invention, a complete transaction of the machine will now be described.

It may be noted that the keyboard B may comprise any suitable number of keys, this depending somewhat upon the capacity of the machine in reference to the different denominations of bills payable thereby. Thus, the one dollar key 42 would be connected to a selector bar 37 that co-operates with the clutch member 32 of the holder C for one dollar bills. On the other hand, the three dollar key 42 would be connected by its selector rod 29 with the selector bars 37 which co-operate with the clutch members 32 of the one dollar and two dollar deliverers D so that, by depression of the single three dollar key, the clutch members 32 associated with the one dollar and two dollar holders 30 will be simultaneously engaged with their ejector arms and subsequent turning of the main actuator E will cause delivery movement of the one and two dollar deliverers D, paying out the two bills supported by said deliverers at one operation.

A simple complete transaction of the machine for the delivery of a twenty dollar bill will now be described; the mechanism for the purpose being shown quite clearly in Fig. 1. Assuming that the parts are in their normal positions, as illustrated in full lines in Fig. 2, a twenty dollar bill is supported by the deliverer D some distance above the pile of bills carried by the holder C therebeneath. Said bill is supported owing to the suction created in the deliverer D and the holder C is maintained in its lowermost position by the same suction acting within the cylinder 4. All that the operator has to do therefore is to depress the twenty dollar key 42 which throw the parts 37 and 32 laterally engaging the latter with its co-operating ejector arm 27. The handle E is now grasped and pulled forwardly, the ejector arm 27 forcing the deliverer D outwardly toward the front of the machine, as shown in dotted lines in Fig. 2, until the free front end portion of the bill projects from the casing A. During such forward movement of the ejector arm 27, the locking member 25 is moved forward also, so that its catch 24 engages over the adjacent end of the transverse bar 18. When the operator takes the bill from the deliverer D in the transaction just referred to, the air-line in the

conduit 13 and connected pipes and deliverer, is broken, air being drawn into the deliverer D through the orifices in its underside and suction in the cylinder 4 being immediately relieved. Were it not for the position of the catch 24 engaging over the bar 18, the control lever 20 would force the holder C upward immediately that the bill is taken from the deliverer, but such action is prevented by the catch until the deliverer returns to its normal position to which it is pulled by the spring 30 as soon as the pressure on the handle E is relieved. During the return movement of the deliverer, the catch 24 of the locking member 25 is being disengaged from the bar 18 and just as the deliverer reaches its normal position, the holder C is released from the catch 24 and is forced upward by the spring 22 connected with the control lever 20. In this way, the pile of bills is raised to the deliverer and the uppermost bill engages the under side of the deliverer and closes the suction openings therein, thereby restoring the unbroken air-line to the deliverer. This action creates a sufficient amount of suction in the cylinder 4 to force the piston 3 downward, thereby restoring the holder C to its normal lowermost position and leaving a bill engaged with the co-operating deliverer, ready to be delivered in a future transaction of the machine.

The holders C are provided with the openings 7 not only for lightening them in construction but in order that when the last bill supported on the holder is delivered to the deliverer D, on restoration of the holder to its lowermost position, not too great a pull will be exerted against the bill to disengage it from the deliverer. While I prefer to use a suction air-line, so to speak, in controlling the operation of the bill holding and delivering mechanisms, I do not wish to be limited in this respect since it would be practicable to use air pressure in accomplishing substantially similar results as are produced in the operation of the present machine.

My invention contemplates quite broadly the provision of the special bill holding and delivering means as co-operatively associated in the manner illustrated and described, whether controlled pneumatically or mechanically. I find that, in paying large sums of money from my machine, it is useful to employ a special mechanism for repeating the action of the deliverer so that two or more bills may be delivered from the machine at a single operation of the controlling instrumentalities.

By reason of the fact that each holder C is movable downwardly away from its deliverer through the action of the operating piston 3, while said holder is raised to supply a fresh bill to the deliverer by means of the spring actuated lever, it will be apparent

that the downward movement of the holder will be relatively slow, whereas said upward movement will be considerably accelerated. This is a desirable feature in the practical 5 operation of the machine because, were the downward movement of the holder a quick movement, there would be a tendency for the bill beneath that engaged with the deliverer to be displaced. The special operating 10 means described eliminates any liability of an improper operation of the parts in the performance of the functions just referred to.

The removal of a bill, or piece of money, 15 from the deliverer D causes the lever 20 and spring 22 to perform their function of moving the holder to supply a fresh bill to said deliverer at the proper time. It is apparent, therefore, that the money paying mechanism 20 is controlled in its action by the removal of the bill from the machine, and I desire to claim this idea broadly whether or not the control is effected in the particular manner and by the special means hereinbefore described.

Having thus described the invention, what is claimed as new is:—

1. In a currency paying machine, the combination of money holders adapted to 30 support piles of bills, a deliverer coöperating with each holder, supporting means for the deliverer, a pivotal connection between the deliverer and its supporting means whereby the deliverer may be moved away 35 from its coöperating money holder for replenishing the latter, means for operating the deliverer, and locking and guiding means intermediate the deliverer and its supporting means for maintaining the deliverer in its normal operating position.

2. In a currency paying machine, the combination of money holders adapted to support piles of bills, a deliverer coöperating with each holder and adapted for movement 45 to carry a bill to a point of deposit, a deliverer support, means for supplying a bill from a coöperating holder to the deliverer, and a loose connection between the deliverer and said support whereby movement of the 50 deliverer independent of the movement aforesaid is afforded to facilitate replenishing of the bills carried by each holder.

3. In a paper currency delivering machine, the combination of relatively movable bill 55 holders and associated deliverers, deliverer supporting means, means controlling relative movement of said parts whereby a bill may be supplied to each deliverer from its holder, and a connection between the said 60 supporting means and each deliverer allowing dual movement of the latter, namely, delivery movement and an independent movement to facilitate replenishing the supply of bills to its holder.

65 4. In a paper currency delivering machine,

the combination of relatively movable bill holders and associated deliverers, means controlling relative movement of said parts whereby a bill may be supplied to each deliverer from its holder, means for causing 70 sliding movement of each deliverer to carry a bill to a delivery point, and a pivotal connection intermediate the last named means and each deliverer permitting independent movement of said deliverer to facilitate access to its bill holder for replenishing purposes and lock means normally preventing the latter movement.

5. In a paper currency delivering machine, the combination of bill holders, deliverers 80 associated therewith, means for supplying a bill from each holder to its deliverer, means for causing delivery movement of each deliverer to carry a bill to a suitable point of deposit, and means pivotally connecting 85 each deliverer with the last mentioned means to permit an abnormal movement of the deliverer to facilitate replenishing of the supply of bills to its associated holder.

6. In a paper money handling machine, 90 a money holder adapted to support a pile of bills, a bill delivery member and its operating means, means to move the holder toward and from the delivery member to effect separation of a bill from the pile, and 95 a connection between the deliverer and its operating means to cause normal delivery movement of the said member and permitting separate movement to facilitate access to the holder.

7. In a paper money handling machine, a movable money holder adapted to support a pile of bills, a bill delivery member, and pneumatic means common to the holder for controlling its movement and to the delivery 105 member for controlling the delivering action of the latter.

8. In a paper money handling machine, a money holder adapted to support a pile 110 of bills, a bill delivery member and its operating means coacting with the holder and delivery member, pneumatic means for effecting movement of the holder away from the delivery member and for causing the delivery member to support a bill supplied thereto from the holder, and other means automatically operable to move the holder toward the delivery member.

9. In a paper money handling machine, a money holder adapted to support a pile 120 of bills, a bill delivery member and its operating means, and pneumatic means controlling the action of the delivery member and adapted to move the holder in relation to the delivery member to effect a separation of a bill from the pile.

10. In a machine of the class described, the combination of a bill delivery member, means for supply bills for delivery by said member, and means controlled by removal 130

of a bill from the delivery member to operate the supply means.

11. In a machine of the class described, the combination of a bill delivery member, means for supplying bills for delivery by said member, and pneumatic means establishing an air line including the delivery member and which line when broken is adapted to cause operation of the bill supply means.

12. In a machine of the class described, the combination of a bill delivery member, means for supplying bills for delivery by said member, and pneumatic means establishing an air line including the delivery member and the bill supply means, and which line broken by removal of a bill from the delivery member is adapted to cause relative movement of said means and member to again supply the member with a bill for delivery.

13. In a machine of the class described, the combination of a bill delivery member, means for supplying bills for delivery by said member, and pneumatic means establishing an air line including the delivery member, means for causing delivery movement of the said member, and means to automatically operate the bill supply means on return movement of the delivery member.

14. In a machine of the class described, the combination of a bill delivery member, means for supplying bills for delivery by said member, pneumatic means establishing an air line including the delivery member, means for causing delivery movement of the said member, means to automatically operate the bill supply means on return movement of the delivery member, and means whereby the supply means is controlled from said air line.

15. In a machine of the class described, the combination of a pneumatic bill delivery member, means for supplying bills for delivery by said member, and pneumatic means controlled by removal of a bill from the delivery member to operate the supply means.

16. In a paper currency paying machine, the combination of holders each adapted to support a pile of bills, a deliverer cooperating with each holder, means for causing relative movement of each holder and its deliverer to supply a bill to the deliverer from the holder, manipulative means for effecting delivery movement of the delivery member, and automatic means for moving the holder toward and from the delivery member controlled by movement of the delivery member, and comprising a spring actuated lever to elevate the holder and thereby engage the uppermost bill thereon with the deliverer.

17. In a paper currency delivering machine, the combination of a plurality of

holders adapted to support piles of bills, a deliverer for each holder, manual means for moving a deliverer to a delivery point, means normally tending to raise the holder of said deliverer to engage the uppermost bill on said holder with the deliverer, and means for restraining the last mentioned means during delivery movement of the deliverer and releasing same on normalizing of the deliverer.

18. In a paper currency delivering machine, the combination of a plurality of holders adapted to support piles of bills, a deliverer for each holder, manual means for moving the deliverer to a delivery point, means normally tending to raise the holder of said deliverer to engage the uppermost bill on said holder with the deliverer, and means for restraining the last mentioned means during delivery movement of the deliverer, and automatically operable to release the holder when the deliverer returns to its normal position.

19. In a paper currency handling machine, the combination of a plurality of holders, a deliverer associated with each holder, manually operable means common to the deliverers to actuate the same, selective mechanism to control operation of the deliverers, means normally tending to raise the holders to engage the uppermost bills thereon with the associated deliverers, and catch mechanism controlled by the movement of the deliverers for restraining the last mentioned means until the deliverers assume predetermined positions in relation to their holders.

20. Delivery mechanism of the class described comprising a holder adapted to support a pile of bills, a deliverer associated with said holder, manual means for effecting delivery movement of said deliverer, a spring actuated lever for raising the holder in relation to its deliverer, and a catch connected to the deliverer operating means to restrain movement of the holder toward the deliverer until the deliverer assumes a predetermined position.

21. In a machine of the class described, the combination of a holder adapted to support a pile of bills, a deliverer adapted to receive and carry a bill to a point of delivery, means for effecting sliding delivery movement of said deliverer, and means permitting raising of the deliverer in relation to the holder to afford access to the latter for replenishing purposes.

22. In a machine of the class described, the combination of a holder adapted to support a pile of bills, a deliverer adapted to receive and carry a bill to a point of delivery, means for effecting sliding delivery movement of said deliverer, and detachable guide means permitting raising of the deliverer in relation to the holder to afford

access, to the latter for replenishing purposes.

23. In a machine of the class described, the combination of a holder adapted to support a pile of bills, a deliverer to carry bills from the holder to a suitable point of delivery, a cylinder, a piston in said cylinder operatively connected with the holder, means for actuating the deliverer, and pneumatic means establishing an air line connected with the cylinder and the holder to cause the piston in the former to move the holder and to cause a bill to be held by the deliverer when supplied thereto.
- 15 24. In a machine of the class described, the combination of a holder adapted to support a pile of bills, a deliverer to carry bills from the holder to a suitable point of delivery, a cylinder, a piston in said cylinder operatively connected with the holder, means for actuating the deliverer, pneumatic means establishing an air line connected with the cylinder and the holder to cause the piston in the former to move the holder and to cause a bill to be held by the deliverer when supplied thereto, and means operable by removal of a bill from the deliverer to impart other movement to said holder.
- 30 25. In a machine of the class described, the combination of a holder adapted to support a pile of bills, a deliverer to carry bills from the holder to a suitable point of delivery, a cylinder, a piston in said cylinder operatively connected with the holder, means for actuating the deliverer, pneumatic means establishing an air line connected with the cylinder and the holder to cause the piston in the former to move the holder and to cause a bill to be held by the deliverer when supplied thereto, and means operable by removal of a bill from the deliverer to impart other movement to said holder and consisting of a lever connected
- 35 40 with the holder and operable automatically to cause relative movement of the holder and deliverer when the latter returns to its normal position after a transaction of the machine,
- 45 50 26. A money handling machine comprising money holders, mechanism for paying out money, and mechanism controlled in its operation by removal of a piece of money

from the machine governing the action of the paying out mechanism.

- 55 27. In a money handling machine, the combination of a holder adapted to support a pile of bills, a deliverer adapted to receive a bill from the holder, means for causing delivery movement of said deliverer, means for effecting a quick relative movement of the deliverer and holder toward one another to supply a bill to the deliverer, and means for causing a comparatively slow relative movement of the deliverer and holder away from one another.

- 60 28. In a money handling machine, the combination of a holder for a pile of bills, a deliverer, means for imparting delivery movement to said deliverer, means for causing quick movement of the holder toward the deliverer to supply a bill to the latter, and means for causing a comparatively slow movement of the holder in returning the same to its normal position.

- 65 29. In a money handling machine, the combination of a holder for a pile of bills, a deliverer, means for imparting delivery movement to said deliverer, means for causing quick movement of the holder toward the deliverer to supply a bill to the latter, and pneumatic means for causing a comparatively slow movement of the holder in returning the same to its normal position.

- 70 30. In a money handling machine for delivering paper currency, the combination of a holder for a pile of bills, delivery mechanism comprising a member adapted to receive a bill preliminary to delivery of the same, means for causing quick relative movement of the holder and said member in alignment with and toward one another to thereby supply a bill to said member, and means for causing a relatively slow movement of said holder and member away from one another.

- 75 31. A money paying machine comprising a pneumatic bill deliverer, and mechanism controlled by removal of a bill from said deliverer governing the action of the latter.

In testimony whereof I affix my signature in the presence of two witnesses.

THOMAS BILYEU.

Witnesses:

FRANK MENEFER,
M. L. MEADOWS.

It is hereby certified that in Letters Patent No. 1,178,377, granted April 4, 1916, upon the application of Thomas Bilyea, of Portland, Oregon, for an improvement in "Paper-Money Deliverers," errors appear in the printed specification requiring correction as follows: Page 4, claim 8, strike out lines 111-112 and insert the words and syllables *erating means, pneumatic means coacting with the holder and delivery member for effect-*; same page and claim, line 113, for the words "away from" read *relative to*; same page, line 129, claim 10, for the word "supply" read *supplying*, and that the said Letters Patent should be read with these corrections therein that the same may conform to the record of the case in the Patent Office.

Signed and sealed this 9th day of May, A. D., 1916.

[SEAL.]

R. F. WHITEHEAD,
Acting Commissioner of Patents.
